UNITED STATES PATENT OFFICE

JOHN H. KOHLER AND AUGUST SCHNEIDER, OF PITTSBURGH, PENNSYLVANIA

FLUE CLEANER

Application filed February 24, 1930. Serial No. 430,581.

Our invention pertains to flue cleaners, and relates especially to devices of the character in which a jet of steam is directed towards the flues of a boiler, and more particularly a locomotive boiler, to blow away the soot, cinders or the like which would otherwise become encrusted in the flues and upon the flue sheet.

In flue cleaners of the above character, as heretofore constructed, steam supply pipes have been passed through the water legs of the boiler, one at each side of the latter, and have been provided at their inner ends with jets for directing the steam against the flue sheet and into the flues. Because any material portion of the steam supply pipes projecting beyond the inner walls of the water legs would be soon burned out in use, it was necessary that the feed nozzles be kept in close proximity to the inner side walls of the water legs, and this, in turn, necessitated that the jets be moved in order that the steam might be directed first towards one section of the flues and then towards another. Such movement of the jets has usually been accomplished by rocking them on an axis, either manually or automatically, the devices being expensive to manufacture, and relatively complex. It has also been proposed to provide a series of steam pipes, equipped with jet nozzles, in such position with respect to the flue sheet that jets of steam could be directed into the flues so as to cover them all without the necessity of any oscillating or other movement of the steam pipes. However, when such devices were close enough to the flue sheet, to be effective, they were liable to burn out, and therefore impracticable.

It is the principal object of our invention to provide a flue cleaner in which a steam jet, or jets, are directed into the flues from a sufficiently short distance to permit the jets to be fully effective, in which the jet or jets will cover all of the flues without the necessity of any moving parts, and which will not be liable to burn out in use. We attain this object by providing a steam pipe, or steam pipes, having a nozzle, or nozzles, arranged in sufficient proximity to the flue sheet for the steam jets to be effective in performing

their required operation, and so as to cover all of the flues, and providing a water jacket for said steam pipe or pipes so as to prevent the same from becoming burned out.

We have shown, by way of example, in the accompanying drawings, and described in the following specification, three forms of flue cleaner constructed in accordance with our invention. It is to be understood, however, that the invention may be embodied in other forms, and that changes may be made in the forms described and shown without exceeding the scope thereof, as defined in the appended claim.

In the drawings:

Fig. 1 is a sectional elevation of a locomotive boiler equipped with one form of flue cleaner constructed in accordance with our invention;

Fig. 2 is a vertical section taken on the line II—II of Fig. 1;

Fig. 3 is an enlarged section taken on the line III—III of Fig. 2, illustrating an appropriate construction of water tube, steam pipe and steam nozzle;

Fig. 4 is an end view of the nozzle;

Fig. 5 is a longitudinal section of a locomotive showing another form of flue cleaner constructed in accordance with our invention applied thereto;

Fig. 6 is a section on the line VI—VI of Fig. 5;

Fig. 7 shows in section still another form of flue cleaner constructed in accordance with our invention applied to a locomotive; and

Fig. 8 is a section on the line VIII—VIII of Fig. 7.

In all of the figures of the drawings, 10 designates the fire box of a locomotive, at one end of which is the flue sheet 11 from which 90 lead the flues 12. The steam head is designated by 13.

Referring particularly to Figs. 1 to 4, the embodiment therein shown includes a water tube 14, of downwardly arched shape, which 95 is secured at each end to the crown sheet of the boiler, so as to make communication, for the circulation of water, with the interior of the latter. Within the water tube are disposed the legs 15 of a pair of steam pipes 16, 100

each of which connects with the steam head 13 and is adapted to receive steam therefrom. Suitable valve means, actuated by a rod 17 adapted to be operated from the cab, controls the admission of steam from the head 13 to the pipe 16. The steam-pipe ends 15 are provided with outlets 18 which extend through the water tube 14, which outlets terminate in steam nozzles. Conveniently the water tube 14 has welded thereto (Figs. 3 and 4) internally threaded collars 19 which surround the outlets 18 and receive nozzles 20 formed with vertically disposed jet openings 21. The outlets 18 are welded to the water tube 14 and are beveled at their ends, as indicated at 22, so as to be engaged by correspondingly beveled portions of the nozzles 20. Thus, when the jets 20 are screwed firmly into the collars 19, a sealed joint will be made between such jets and the outlets 18, making the whole unit steam-tight, and at the same time permitting the jets to be removed, for cleaning purposes, when desired.

The vertically elongated shape of the orifices 21 of the nozzles 20 is such that these jets will cover an entire section of the flues from top to bottom, the section thus covered also being of considerable width. The number, and lateral disposition, of the jets is such that all of the flues will be covered.

It will be noted that by placing the jets at the proper distance from the flue sheet the full force of the issuing steam can be utilized in cleaning the flues, and that such cleaning of all the flues is accomplished without the necessity of providing any moving parts. By thus arranging the jets, in combination with water cooling means for the steam supply pipes therefor, a very simple and economical, and yet efficient, flue cleaning device is produced, without there being any danger of the parts being burned out under the intense heat to which they are subjected.

In the embodiment of our invention shown in Figs. 5 and 6, utilization is made of the water tubes which are commonly employed for supporting the refractory arch structure of the fire box, although it may be preferable to make such water tubes, as indicated at 23, of a somewhat larger diameter than is usual. In each of the arch tubes is disposed the end 24 of a steam pipe 25 which connects with the steam head 13. The extremities of the steam pipe ends 24 project through the arch tubes, 55 and are formed to constitute nozzles 26 which direct the steam into the flues in the manner described above in connection with Figs. 1 to 4, the nozzles, and the orifices thereof, being of course constructed so as to give the required upward direction to the jets. In this case a control valve 27 is shown as provided for each of the steam pipes 25, so that the jets can be selectively controlled.

Figs. 7 and 8 illustrate an application of our invention to a locomotive boiler of the

siphon type, shown as having two siphon legs 28. In each of the siphon legs is disposed the end 29 of a steam pipe 30, equipped with suitable control valve means, and making connection with the steam head 13. Each of the steam pipe ends 28 is provided with a pair of nozzles 31 which project forwardly through the front wall of the siphon leg, directing the steam jet into the flues, in the manner above described.

We claim:

The combination with a locomotive boiler provided with a fire-box having a flue sheet at one end and a back-wall at the other end thereof, of a flue cleaner comprising steam-containing means disposed in said fire-box and connected with the live steam space of said boiler, said steam-containing means having nozzles disposed closer to said flue sheet than to said back-wall at a sufficient distance from said flue sheet and so directed that live steam issuing therefrom will impact against substantially all the flue sheet, and a water-jacket disposed within said fire-box and surrounding said steam-containing means, for the purposes set forth.

In testimony whereof, we hereunto sign our names.

JOHN H. KOHLER
AUGUST SCHNEIDER.
